[57] CLAIM

The ornamental design for a compressor shroud, as shown and described.

DESCRIPTION

FIG. 1 is a top view of a compressor shroud showing the new design;

FIG. 2 is a front view thereof;

FIG. 3 is a rear view thereof;

FIG. 4 is a bottom view thereof; and,

FIG. 5 is a right view thereof, which is a mirror image of the opposite right side not shown.

The broken line showing of a bracket, in FIGS. 1, 2 and 3 is for illustrative purposes only and forms no part of the claimed design.

FIG. 1

FIG. 2

FIG. 3

FIG. 4

FIG. 5
